UNITED STATES PATENT OFFICE.

RALPH W. BAILEY, OF WEST NEWBURY, MASSACHUSETTS.

PROTRACTOR ATTACHMENT FOR CENTER-FINDING INSTRUMENTS.

SPECIFICATION forming part of Letters Patent No. 679,934, dated August 6, 1901.

Application filed April 19, 1901. Serial No. 56,568. (No model.)

To all whom it may concern:

Be it known that I, RALPH W. BAILEY, of West Newbury, in the county of Essex and State of Massachusetts, have invented certain new and useful Improvements in Protractor Attachments for Center-Finding Instruments, of which the following is a specification.

This invention has for its object to provide a protractor attachment for a center-finding instrument, such as a center-square, whereby said instrument can be conveniently used in making marks subdividing the side of a disk or the end of a cylinder into equal divisions or segments of any desired number.

The invention consists in the improvements which I will now proceed to describe and claim.

Of the accompanying drawings, forming a part of this specification, Figure 1 represents a plan view of a protractor attachment embodying my invention. Fig. 2 represents an edge view of the same. Fig. 3 represents a section on line 3-3 of Fig. 1. Fig. 4 represents a plan view of the jointed holder, the protractor being removed. Figs. 5 and 6 represent perspective views of the pointers engaged, respectively, with the holder and the protractor. Figs. 7 and 8 are plan views showing the attachment engaged with a center-square, said figures illustrating the mode of operation of the square and the attachment. Fig. 8^a represents a plan view of a center-square provided with a modification of my invention. Fig. 9 represents a plan view of said modification. Fig. 10 represents an edge view of the same. Fig. 11 represents a section on line 11-11 of Fig. 8. Fig. 12 represents a perspective view of a part of said modification.

The same reference characters indicate the same parts in all the figures.

In the drawings, *a* represents an ordinary center-square, which comprises a blade and a head having two faces 22 arranged at right angles with each other and at equal angles with the edge 3 of the blade of the square, so that when the faces 22 are applied to the periphery of the cylinder or disk 4 the edge 3 will intersect the center of the said disk, as indicated in Figs. 7 and 8.

My improved attachment hereinafter de-

scribed enables a circle 4 of any diameter within the capacity of the blade of the square to be marked into any desired number of subdivisions of equal length by the use of a suitable marking-tool guided by the edge 3 of the square, the said attachment enabling the operator to adjust the square so that after each adjustment a mark can be made upon the work, forming a subdivision of predetermined length.

I will first describe the preferred embodiment of my invention. (Shown in Figs. 1 to 8, inclusive.) In said figures, *b* represents a protractor, which is preferably a complete circle or disk and is rotatably mounted upon a holder, which holder has means for detachable and adjustable connection with the blade of a center-square. In this embodiment of my invention the holder is composed of two parts *c* and *c'*. The part *c* is adapted to be fixed to the center-square and is hereinafter termed the "fixed part," while the part *c'* is jointed to the part *c* and adapted to swing thereon with the protractor *b*, so that the holder can be pressed against the periphery of the disk or cylinder 4, and is hereinafter referred to as the "swinging part." The fixed part *c* of the holder in this embodiment of my invention has an ear 5, adapted to bear against the under side of the blade of the square and constituting a clamp member, and an adjustable clamp member 6, movable toward and from the member 5 and adapted to bear on the upper side of the blade of the square. The member 5 is provided with screws 77, extending upwardly through the member 6 and provided with nuts 8, which when turned downwardly cause the members 5 and 6 to clamp the square-blade. 9 is a bearing-screw inserted in the fixed part *c* and adjustably supporting the inner edge of the clamp member 6. The clamp members 5 and 6 are adapted to be engaged with the square-blade at any distance from its head, as will be readily seen. The protractor *b* is offset from or located below the clamp members, as shown in Figs. 2 and 3, so that the periphery of the protractor bears on the periphery of the disk 4 when the blade bears on the end or side thereof. The swinging part *c'* of the holder is connected with the fixed part *c* by means of a tubular stud, which

as here shown, comprises an externally-threaded member 10 and an internally-threaded member 11, the said members being screwed together, as indicated in Fig. 3, forming a tubular stud having flanges 12 and 13. The meeting portions of the parts *c* and *c'* of the holder have coinciding orifices, which receive the outer member 11 of the stud, said orifices being countersunk to receive the flanges 12 and 13. The swinging part of the holder is adapted to turn freely on the member 11 of the stud, the latter being held from rotating by a screw-thread engagement with the member 10, which in turn is held from 15 rotating by being rigidly connected in any suitable way with the fixed part *c* of the holder. *d* represents a coiled spring which is located within the tubular stud, its ends projecting from the stud, one end being engaged at *d'* with the fixed part *c*, while the other end is engaged at *d''* with the swinging part *c'*. The spring acts to swing the part *c'* and the protractor *b* thereon toward the disk or cylinder 4, on which the square 25 is placed, thus holding the periphery of the protractor in close rolling contact with the periphery of the part 4 to be marked. It will be seen that the hollow stud connecting the two parts of the jointed holder affords a 30 convenient receptacle for the spring, enabling a coiled spring of considerable power to be used without projecting objectionably from the holder. *e* represents a stud affixed to the end of the swinging part *c'* of the holder and 35 projecting upwardly therefrom. Said stud has a flange 15, which supports the protractor *b*, and a cylindrical portion 16 above the flange, which constitutes a journal on which the protractor is adapted to rotate. Above the journal portion 16 the stud is reduced and screw-threaded, and with this screw-threaded portion is engaged an internally-threaded sleeve 17, having a flange 18 at its lower end. *f* represents a pointer having a hub *f'*, which 40 rounds the journal portion 16 of the stud and bears upon the upper surface of the protractor *b*. The flange 18 bears upon the upper surface of the hub and holds the under surface thereof in frictional engagement with the upper surface 45 of the protractor, so that the finger *f* rotates with the protractor and is adjustable thereon. *g* represents another pointer, having a hub *g'*, which hub surrounds the sleeve 17 and bears on the upper surface of the 50 flange 18. *19* represents a spring which is interposed between the upper side of the hub *g'* and the under side of a nut 20, which is engaged with an external screw-thread formed on the sleeve 17. The spring 19 holds the 55 hub *g'* closely against the flange 18, and as said flange is affixed to the stud *e*, which in turn is affixed to the part *c'* of the holder, it follows that the finger *g'* does not revolve, but remains stationary over the protractor 60 when the latter is rotated. The spring 19 and the nut 20 enable the finger *g* to be adjusted to any position desired. The under surface

of the nut 20 and the upper surface of the hub *g'* are dished or concaved, as shown in Fig. 3, to prevent the sidewise displacement 70 of the spring 19.

A center-square provided with the described attachment may be operated as follows: The center-square is placed upon the circle 4 to be marked, the attachment being adjusted 75 so that the periphery of the protractor will be held in close contact with the periphery of the circle 4 by the spring *d*. The fixed or non-revolving pointer *g* is then adjusted to a position over the zero-mark on the protractor, the other or revolving finger *f* being adjusted at a distance from the fixed pointer corresponding to the length of the subdivisions to be formed on the circle 4, the adjustment depending upon the diameter of the 80 circle 4. The operator then, after marking the work by drawing a scratch-awl along the edge 3 of the center-square when the latter is in the position shown in Fig. 7, turns the square until the points of the two fingers 90 coincide, as shown in Fig. 8, and then again marks the work by moving the marking-tool along the edge 3. The pointers are then readjusted as before and the above-described operation is repeated until the entire circle 95 has been subdivided into divisions of equal length.

It is obvious that a series of orifices 22 may be made in the protractor, as shown in Fig. 8^a, either of which may receive a pin which 100 will serve as an equivalent of the finger *f*, said finger being omitted.

In Figs. 8, 9, 10, 11, and 12 I show a modification of my invention in which a circular protractor *B* is mounted to rotate on a stud 105 *E*, which is journaled in a holder *C*. Said holder is formed to extend across the blade of a center-square, and its under side is recessed to form shoulders *C'* *C''*, extending over the edges of the said blade. The shoulder *C''* has a set-screw *C'* arranged to abut against the rear edge of the blade and clamp the holder to the blade, the front or marker-guiding edge 3 of the blade bearing against the shoulder *C'*. The stud *E* is arranged so 115 that its center coincides with the edge 3. The stud is provided at its upper end with a head having an inner edge *E'*, which extends across the axial center of the stud. From said head two ears *E''* extend inwardly over a marker-guiding strip or blade *F*, which is clamped against the upper surface of the protractor *B* by set-screws *E'*, engaged with 120 said ears. The blade *F* can therefore be adjusted at any desired angle with the blade of the center-square, its guiding edge 30 extending across the axial center of the stud *E*. The blade *F* can therefore be adjusted by the aid of the protractor to stand at any 125 desired angle with the blade of the center-square, the marking edges of the two blades guiding the marking-tool in making two radial marks on the circle 4 when the center-square is in a given position, so that by 130

moving the center-square on the work after two marks have been made to bring the edge 30 over the mark previously made by the edge 3 the edge 3 will be advanced to position for the next mark, and so on until the entire circle has been subdivided. In this modification the protractor covers the center of the circle 4, so that the marks cannot be extended inwardly as far as by the use of 10 the embodiment of my invention shown in Figs. 1 to 8, inclusive.

I claim—

1. An appliance of the character specified, comprising a graduated protractor, and a 15 jointed holder composed of a fixed part adapted for adjustable connection with a center-finding instrument, and a swinging part supporting the protractor.

2. An appliance of the character specified, 20 comprising a graduated protractor, and a jointed holder composed of a fixed part adapted for adjustable connection with a center-finding instrument, and a swinging part supporting the protractor, the said holder having a spring whereby the swinging part and the protractor are pressed yieldingly in one 25 direction.

3. An appliance of the character specified, comprising a graduated protractor, a holder 30 on which said protractor is rotatively mounted, said holder having clamping members adapted for detachable and adjustable connection with the blade of a center-square, and a pointer adjustably engaged with the holder 35 and coöperating with the graduated surface of the protractor.

4. An appliance of the character specified, comprising a graduated protractor, a holder 40 on which said protractor is rotatively mounted, said holder having clamping members adapted for detachable and adjustable connection with the blade of a center-square, a pointer adjustably engaged with the holder 45 and coöperating with the graduated surface of the protractor, and a pointer adjustably engaged with the protractor and coöperating with the graduated surface thereof, and with the fixed pointer engaged with the holder.

5. An appliance of the character specified, comprising a protractor, a holder having a 50 stud on which the protractor is rotatably mounted, a pointer adjustably engaged with the stud, and a pointer engaged with the protractor.

6. An appliance of the character specified, 55 comprising a protractor, a holder having a stud on which the protractor is rotatably mounted, clamping members on said stud, a pointer having a hub grasped by said clamping members, and a pointer having a hub 60 held in frictional contact with the protractor by a clamping member on the stud.

7. A proportional protractor comprising a graduated disk, a jointed holder therefor composed of a fixed part having means for adjustable connection with a center-finding instrument, and a swinging part on which the disk is rotatably mounted, a tubular stud secured to the fixed part and having a rotative connection with the swinging part, and a 70 coiled spring located within said tubular stud, the ends of the spring projecting from the stud, one of said ends engaging the fixed part of the holder and the other the swinging part.

8. The combination with a center-finding 75 instrument comprising a head having a plurality of faces adapted to bear simultaneously on the periphery of a circular piece of work, and a blade having a straight-edge arranged to extend across the center of said piece when 80 the said faces are brought to a bearing on the periphery thereof, of a protractor adjustable on said blade toward and from said head, said protractor being provided with means for engagement with the work in any position 85 to which it may be adjusted, whereby the protractor may be adapted to coöperate with the center-finding instrument in subdividing pieces of work of different diameters.

In testimony whereof I have affixed my signature in presence of two witnesses.

RALPH W. BAILEY.
